UNITED STATES PATENT OFFICE.

CHARLES F. SHOEMAKER, OF CLEVELAND, OHIO.

MACHINE FOR SHAPING AND FITTING SPRINGS.

SPECIFICATION forming part of Letters Patent No. 223,454, dated January 13, 1880.

Application filed July 1, 1879.

To all whom it may concern:

Be it known that I, CHARLES F. SHOEMAKER, of Cleveland, in the county of Cuyahoga and State of Ohio, have invented a certain new and Improved Machine for Shaping and Fitting Carriage-Springs; and I do hereby declare that the following is a full, clear, and complete description of the same.

This invention relates to a machine for bending or shaping the leaves or plates of carriage-springs, whereby the series of leaves or plates composing the spring are adapted to each other in their curvilinear relation.

The construction of the said machine and the practical operation of the same will be found fully set forth and described in the following specification, and illustrated by the drawings making a part thereof, in which—

Figure 1 is a side elevation of the machine. Fig. 2 is a longitudinal section. Fig. 3 is a sectional plan view. Fig. 4 is a vertical transverse section. Figs. 6, 7, 8, and 9 are enlarged views of detached sections. Fig. 5 will be referred to.

Like letters of reference refer to like parts in the several views.

Within a suitably-constructed frame, A, Fig. 1, is arranged a carriage, B, the ends of which are respectively adapted to the guides or ways C on the inner side of the ends of the frame. Said carriage has given to it a vertical reciprocating movement by the following devices: Transversely in each end of the frame A is journaled a shaft, D, Figs. 3 and 4, immediately under the ends of the carriage. From the shafts project a pair of arms, E, Figs. 2 and 4. Said arms are attached to the ends of the carriage, respectively, by links F, and form, in connection with the arms, a toggle or knee joint, as seen in Fig. 2. The two knee-joints are connected to each other by a link, G, whereby the joints are worked together by a lever, H, for operating the carriage, for a purpose presently shown. The carriage B, alluded to, is hollow, and to the top thereof is secured a former, I, consisting of a metal bar. The middle of the former is supported on a standard, J, screwed into the top of the carriage. Each end of the former terminates in an eye, a, Fig. 5, whereby the ends are pivoted, respectively, in the clips K, Figs. 1 and 2. To the clips are pivoted adjusting-screws L, projecting down,

through slots into the hollow of the carriage, to the top of which they are made fast by a nut above and below the top, as seen in Fig. 2. 55

Between the central standard, J, supporting the former, and the adjusting-screws L is an auxiliary standard, c, which is also secured to the top of the carriage in the slots by means of a nut above and under the slot, as are the 60 adjusting-screws L, above referred to.

M is a shaft having its bearings in the top of the carriage, from near the middle of which project upward fingers or guards N above the former, and against the side of which they 65 rest. The said fingers have a lateral vibratory movement by means of an arm, O, Fig. 4, on the end of the shaft.

To the arm is attached one end of a rod, P, also indicated by the dotted lines P in Figs. 70 1 and 2. The lower end of the rod is made fast to the floor. Hence, as the carriage moves upward the rod draws upon the arm and rotates the shaft, thereby causing the fingers to recede from the side of the former. *Per contra*, 75 as the carriage descends the rod pushes up the arm, causing the fingers to rest against the former, as shown in the drawings. The purpose of the fingers will hereinafter be shown.

In each side of the upper part of the frame 80 A are elongated curvilinear openings Q, Fig. 1, in each of which is fitted a sliding journal-box, R, in which the ends of the shaft S have respectively their bearings, as seen in Fig. 4. To said shaft S is secured a roller-carriage, to 85 which is given a reciprocating longitudinal movement by connecting-rods T, attached to the shaft, and respectively to the cranks U of the shaft V, carrying the cog-wheel W, whereby the cranks are revolved by the engagement of 90 said cog-wheel with other appropriate gearing.

The roller-carrier above alluded to consists of a pair of cheeks, A' and B', Fig. 4, secured to the shaft by set-screws n'. An enlarged inside view of a cheek is shown in Fig. 6, and 95 an upper edge view of the same in Fig. 7. In the inner side of the cheeks are made dovetail radial grooves C', Figs. 6 and 7, in which are fitted, respectively, the slides 1, 2, 3, and 4. A detached view of the slide 1 is shown in 100 Fig. 8. Each of said slides is provided with an adjusting-screw, d, for moving them in the grooves. Said grooves and slides may be more or less in number.

Passing upward through each of the slides is a stem, D'. The lower end of the stem is a plate, and is retained in the hollow of the slide by a strap, E', under which it is free to move longitudinally in the slide. The upper part of the stem is reduced in size, forming a rod, around which is a spring, F'. The upper end of the stem projects through the end of the slide, and is prevented from falling therefrom by a pin, e, Fig. 8.

To the lower end of each of the slides is secured a roller, G', provided with a flange, f, Fig. 9.

Both cheeks of the carrier are substantially alike, and when secured on the shaft S the grooved sides face each other, as shown in Fig. 4, in which it will be seen that the cheeks and rollers approximate near to each other, but do not touch, there being a narrow space between them, for a purpose presently shown.

Longitudinally on the top of the frame A is secured a beam, H', Figs. 1 and 2. Projecting downward through each end of the beam is a hanger, I', having in the side thereof a groove, wherein is fitted a bending-arm, J', depending therefrom into the frame below the rollers, as will be seen in the drawings. Said bending-arms J' are prevented from dropping from the hangers by a set-screw passing through a slot in the end of the arm into the hanger. The slot permits the arm to move vertically, and the arm is forced downward by a spring, K', the ends of which rest upon the top of the arms, the central part being confined by the screw L', and more or less tension given to the spring thereby.

The practical operation of the above-described machine is substantially as follows: As hereinbefore said, the purpose of the machine is for bending the several leaves composing a spring, Fig. 5, which may be more or less in number, and of different lengths and widths. To this end the former I, above referred to, is given the curvature desired for that of the spring, or, rather, for one of the leaves thereof, which let it be supposed to be the first or longest one of the number. This curvature is readily obtained to the former by means of the adjusting-screws L and the adjustable standards J and e, above referred to, by which means any desirable degree of curvature can be given to the former.

The leaves or plates to be bent are heated in a furnace, from which one is taken and laid lengthwise upon the former, as indicated by the dotted line x x, Figs. 1 and 2.

That the heated leaf may lie straight upon the former is the purpose of the fingers or guards N, against which the edge of the leaf is laid when placing it flatwise thereon.

Immediately upon laying the leaf upon the former the carriage B is moved upward by means of the lever H operating the mechanism above described for actuating said carriage. As soon as the carriage begins to move upward the fingers or guards N move back from the side of the former, to make way for

the rollers on that side thereof, at the same instant the ends of the leaf come in contact with the ends of the arms J'. As the carriage 70 continues to rise the ends of the leaf are bent down upon the former, and at the same time the leaf comes in contact with the rollers, (to which a reciprocating movement had been previously given by the cranks U U,) and by them 75 is rolled down upon the former. The pressure of the rollers upon the metal as they roll backward and forward upon it conforms it to the shape of the former. After a few passes of the rollers over the leaf the carriage B is 80 then lowered and the leaf removed from the former, to be replaced by another. As the carriage begins to recede from the rollers the fingers or guards N at the same time begin to assume an upright position, and by the time 85 the carriage has reached its lowest point the fingers are brought against the side of the former, for the purpose above specified.

It will be observed that the rollers of the cheek A' of the roller-carrier run along upon one side of the leaf, near the edge thereof, and that the rollers of the cheek B' roll along upon the opposite side, near the edge, thereby leaving a narrow space along the middle of the leaf from end to end untouched by the 95 rollers, and that the flanges of the rollers while in operation extend below the edges of the former, thereby keeping the leaf properly in place on the former while being acted upon by the rollers. The cheeks of the roller-carrier, being free to vibrate during their reciprocating movement, permit the rollers to readily conform to the curve of the former while being forced down upon the leaf thereon by the spring F', the tension of which forces the rollers upon the leaf with more or less energy, according to the force of the upward movement of the carriage B, that may be exerted by the operator by means of the lever H, which may be more or less, as the nature of the case may 100 demand. Furthermore, the pressure of the rollers upon the former and leaf can be increased or diminished by screwing down or up the slides 1, 2, 3, and 4 by means of the adjusting-screws d, above alluded to, thereby 105 bringing the rollers nearer to or distant from the former. The principal object of the slide, however, is to regulate the position of the rollers in respect to the curvature of the former—that is to say, to adjust and conform the line or range of the rollers to the curvature of the former, so that the several rollers shall act with equal pressure upon the leaf.

The sliding journal-boxes of the shaft carrying the cheeks of rollers move in a curved opening, thereby causing the shaft and the cheeks to move in a curvilinear reciprocating manner, and at the same time having a vibratory movement with the shaft. This freedom 125 of movement allows the cheeks of rollers or roller-carrier to readily and easily adjust the rollers to the differences in the curve required for the leaves of variously-shaped springs, 130

which is considerable; but the cheeks of rollers can be adjusted to meet this difference, and the former adjusted in conformity therewith.

5 As above said, the two sets of rollers do not roll over the whole width of the plate or leaf. There is a space between the two sets of rollers as they face each other wide enough to permit the arms J' to pass between them. This 10 is to allow the rollers to operate upon a leaf shorter than the length of the cheeks. To this end the arms J' are moved closer together and between the cheeks and rollers, so that the ends of the arms may engage the ends of 15 the leaf or plate to be bent on the former. In thus having the two sets of rollers with a space between, very short leaves can be bent and operated upon by them, which could not be done if the rollers extended across the 20 leaf, as the bending-arms J' could not be adjusted to engage the ends of a leaf shorter than the length of the cheeks, as aforesaid.

N' is a counter-balance for assisting in the operation of the carriage B.

25 As hereinbefore said, the cheeks of the roller-carrier are secured to the shaft S by means of set-screws, thereby rendering them adjustable on the shaft in order to adapt the rollers to different-width springs—that is to 30 say, the cheeks can be moved closer to or farther from each other, according to the width of the leaves for the springs.

The springs F' on the stems of the rollers allow a ready adaptation of the several rollers 35 to the curvature of the former, and prevent undue strain being exerted upon any particular roller in excess of that of the others.

What I claim as my invention, and desire to secure by Letters Patent, is—

40 1. In machines for bending and shaping plates for carriage-springs, in combination with the rollers G', a roller-carrier consisting of the cheeks A' B', secured to a rock-shaft

having its axial bearings in sliding boxes R R, fitted in curvilinear openings in the frame A, 45 for obtaining to the said carrier a rocking and curvilinear action, and pitmen and cranks U U, for imparting a reciprocating movement to said carrier, substantially as described, and for the purpose set forth. 50

2. In machines for making carriage-springs, the combination, with the rollers G', a roller-carrier consisting of the cheeks A' B', arranged upon a rock-shaft in such manner that said cheeks have a parallel facial relation to each other, and radial slides 1 2 3 4 and their respective adjusting-screws d, substantially in the manner as described, and for the purpose specified. 55

3. In combination with the slides 1 2 3 4 of 60 the cheeks A' B', the stems D', springs F', and rollers G', substantially as and for the purpose set forth.

4. Arranged in relation to the roller-carrier in two parts, herein described, and in combination therewith and with the carriage B, the adjustable bending-arms J', substantially as set forth, and for the purpose specified. 65

5. In machines for making springs, in combination with the former I and rollers G', the 70 cheeks A' B', provided with set-screws n', for adjusting said cheeks upon the rock-shaft S, as and for the purpose specified.

6. In machines for bending and fitting plates for springs, the combination of the carriage B, carrying the adjustable former I, guard-fingers N, and shaft M, knee-joints, link G, and lever or other suitable mechanism for imparting a reciprocating movement to said carriage, substantially as described, and 80 for the purpose set forth. 75

CHARLES F. SHOEMAKER.
